**HOUSING FOR A TELEPHONE AMPLIFIER
ACCESSORY OR SIMILAR ARTICLE**

Joseph H. Prager, North Hollywood, Calif., assignor of
forty percent to Nichimen Co., Ltd., Tokyo, Japan, a
corporation of Japan

Filed Nov. 8, 1963, Ser. No. 77,336

Term of patent 3½ years

(Cl. D26—14)

*Fig. 1.**Fig. 3.**Fig. 2.**Fig. 4.*FIG. 1 is a perspective view of a housing for a telephone amplifier accessory or similar article showing my new design, the broken line showing of a telephone base and handset being for illustrative purposes only;

FIG. 2 is an enlarged top plan view of the same;

FIG. 3 is an enlarged elevational view of one end thereof, as viewed from the right in FIG 1;

FIG. 4 is an elevational view of the other end, as viewed from the left in FIG. 1;

FIG. 5 is a front elevational view; and

FIG. 6 is a rear elevational view.

The dominant features of my design reside in the portions shown in full lines.

The bottom, not shown, is open, the material being of no material thickness and forming a substantial intaglio of the top surface.

I claim:

The ornamental design for a housing for a telephone amplifier accessory or similar article, substantially as shown and described.
